ATTORNEY

UNITED STATES PATENT OFFICE.

ROBERT B. KUHN, OF CANTON, OHIO.

SPARK-IGNITING PLUG.

No. 820,797.

Specification of Letters Patent.

Patented May 15, 1908.

Application filed May 10, 1905. Serial No. 259,726.

To all whom it may concern:

Be it known that I, ROBERT B. KUHN, of the city of Canton, county of Stark, and State of Ohio, have invented a new and useful Improvement in Spark-Igniting Plugs, of which the following is a specification.

The invention relates to a plug for igniting the gas in the cylinder of an explosive-engine by means of an electric spark; and the object 10 of the improvement is to shape the several parts and mount them on or around a single stem in such a manner that there is a tapered or wedge-acting contact between the insulation-tube and both the stem and case and 15 that all the parts can be drawn and held tightly together without danger of breaking by reason of excessive or uneven compression or of their unequal expansion and contraction under varying degrees of temperature.

20 This object is attained by the construction and arrangement illustrated in the accompanying drawings, in which—

Figure 1 is a sectional view of an explosive-engine cylinder, showing the igniting-plug applied thereto; Fig. 2, a longitudinal section of the plug; Fig. 3, a detached perspective view of the case and the stem with the insulating-tube thereon in proper relation for assembling; and Fig. 4, a detached view of the 30 spiral spring, the set-nut, and the binding-nut in proper relation for assembling.

Similar numerals refer to similar parts throughout the drawings.

The case 1 is tubular in general form, and is 35 detachably secured, preferably by screwing, into the aperture 2 in the head 3 of the engine-cylinder 4. The through-cavity 5 of the case is provided with the endwise-tapered section 6, having the reduced end directed 40 outward, and the section 7 of the case-cavity is preferably slightly larger than the enlarged end of the tapered section.

The insulation-tube 8 is adapted to be entered from the inner end into the cavity of 45 the case and is provided externally with the endwise-tapered section 9, which is adapted to neatly fit and bear against the tapered section of the cavity. The inner end section 10 of the insulation-tube is preferably made 50 slightly less in diameter than the adjacent wall of the cavity of the case, thus forming the constricted, but continuous, annular interval 11 between the insulation-tube and the case at the mouth thereof. The section 12 of the 55 insulation-tube between the tapered and inner end sections is preferably reduced in di-

ameter to form the considerably annular cavity 13 within the case, and the cavity of the case is preferably reamed out to form the annular groove 14 at the inner end of the tapered section, so as to extend the considerable cavity squarely to this point.

The stem 15 is adapted to be entered from the inner end into the through axial aperture 16 of the insulation-tube and is provided with 60 the head 17, having its side 18 concaved to neatly fit and bear against the tapered or cone-shaped inner end 19 of the insulation-tube. The head 17 of the stem constitutes one of the electrodes of the plug, and the 70 other electrode is preferably composed of the end of the wire 20, attached to the case and terminating at a point adjacent to the stem-head.

The insulation-collar 21 surrounds the projecting outer end 22 of the insulation-tube and bears against the outer end of the case. The set-nut 23 is adjustably secured, preferably by screwing, on the shank 24 of the stem, and the intervening spring 25, which may be a 80 coil-spring, as shown, is provided and adapted to bear against the outer end of the insulation-collar and the inner side of the set-nut, and the thimble or sleeve 26 may be provided on the inner side of the nut, which is adapted 85 to enter into the cavity of the spring and hold the same in proper lateral position. By this construction and arrangement all the parts of the plug can be tightly drawn together by applying the set-nut on the stem and screwing 90 it to compress the spring to the desired pressure. In so doing the tapered or wedge-acting contact of the insulating-tube with both the case and the stem-head brings these parts more tightly together than could be 95 done with a square-shouldered contact, and the resiliency of the spring permits a greater pressure to be applied to the parts without danger of their being broken by an unequal expansion or contraction of the parts.

100 What I claim as my invention, and desire to secure by Letters Patent, is—

1. An igniting-plug comprising a case with an electrode on its inner end and having a cavity with an outwardly-reduced tapered 105 section therein, an insulation-tube in the cavity with a cone-shaped inner end and having a tapered section thereon adapted to fit and bear against the tapered cavity-section, a stem in the tube having an electrode-head on 110 the inner end with a concave side adapted to fit and bear against the cone-shaped tube

end, an insulation-collar around the outer end of the tube and bearing against the outer end of the case, a spring around the outer end of the stem and bearing against the outer end of the collar, and adjustable securing means on the outer part of the stem adapted to bear against the spring.

2. An igniting-plug comprising a case with an electrode on its inner end and having a cavity with an outwardly-reduced tapered section therein, an insulation-tube in the cavity with a cone-shaped inner end and having a tapered section thereon adapted to fit and bear against the tapered cavity-section, a stem in the tube having an electrode-head on the inner end with a concave side adapted to fit and bear against the cone-shaped tube end, an insulation-collar around the outer end of the tube and bearing against the outer end of the case, and adjustable securing means on the outer part of the stem adapted to bear against the collar.

3. An igniting-plug comprising a case with an electrode on its inner end and having a cavity with an outwardly-reduced tapered

section therein, an insulation-tube in the cavity having a tapered section thereon adapted to fit and bear against the tapered cavity-section, a stem in the tube having an electrode-head bearing against the inner end of the tube, an insulation-collar around the outer end of the tube and bearing against the outer end of the case, a spring around the outer part of the stem and bearing against the outer end of the collar, and adjustable securing means on the outer part of the stem adapted to bear against the spring.

4. In an igniting-plug, an insulation-tube with a cone-shaped inner end and a stem in the tube having a head on the inner end with a concave side adapted to fit and bear against the cone-shaped tube end.

In testimony whereof I have signed my name to this specification in the presence of two subscribing witnesses.

ROBERT B. KUHN.
